(57) **CLAIM**

The ornamental design for a handheld light, as shown and described.

DESCRIPTION

FIG. 1 is a top, front, right side isometric view of a first embodiment of a handheld light, wherein the head assembly and the tail cap assembly have been reduced to broken lines; FIG. 2 is a bottom, rear, left side isometric view of the handheld light shown in FIG. 1;

FIG. 3 is a front view of the handheld light shown in FIG. 1;

FIG. 4 is a right side view of the handheld light shown in FIG. 1;

FIG. 5 is a rear view of the handheld light shown in FIG. 1; FIG. 6 is a left side view of the handheld light shown in FIG. 1;

FIG. 7 is a top view of the handheld light shown in FIG. 1; and

FIG. 8 is a bottom view of the handheld light shown in FIG. 1.

FIG. 9 is a top, front, right side isometric view of a second embodiment of a handheld light, wherein the head assembly and the tail cap assembly have been reduced to broken lines; FIG. 10 is a bottom, rear, left side isometric view of the handheld light shown in FIG. 9;

FIG. 11 is a front view of the handheld light shown in FIG. 9;

FIG. 12 is a right side view of the handheld light shown in FIG. 9;

FIG. 13 is a rear view of the handheld light shown in FIG. 9;

FIG. 14 is a left side view of the handheld light shown in FIG. 9;

FIG. 15 is a top view of the handheld light shown in FIG. 9; and,

FIG. 16 is a bottom view of the handheld light shown in FIG. 9.

The broken lines shown in the drawings represent portions of the handheld light that form no part of the claimed design.
